UNITED STATES PATENT OFFICE.

JAMES A. CHARTER, OF CHICAGO, ILLINOIS.

GAS-ENGINE.

1,366,445.

Specification of Letters Patent. Patented Jan. 25, 1921.

Application filed September 15, 1919. Serial No. 323,888.

To all whom it may concern:

Be it known that I, JAMES A. CHARTER, a citizen of the United States, residing at Chicago, in the county of Cook and State of Illinois, have invented a certain new and useful Improvement in Gas-Engines, of which the following is a specification.

This invention relates to internal combustion engines, particularly those using heavy 10 grades of fuel oil. It is well understood in the art that when the normal operation of an engine sucking air into itself is relied upon to have the ingoing air draw in fuel oil through the carbureter, there are one or more 15 periods, particularly as a large volume of air is being drawn in, when the effective oil drawing power is very slight, with the result that heavy oil if drawn in at all will not be properly atomized.

20 The object of this invention is to provide an engine of this class with independent mechanism for forcing oil into the engine in properly, finely divided condition whenever and wherever it is, by prior investigation, 25 decided that it is wanted.

The invention consists in providing at a suitable point in the engine intake an atomizing or injecting apparatus controlled entirely independently of the engine itself but 30 if desired driven by the engine itself which will at predetermined times or points in the movement of the engine deliver the properly, finely divided oil into the engine. The invention further consists in valve mechanism 35 for controlling this independent injecting or atomizing mechanism to, as is desired, vary the quantity of materials delivered by it to the engine, the device being usable on any sort of liquid fuel, such as gasolene, kerosene, alcohol, or any of the fancy patented 40 mixtures now on the market.

More particularly the invention consists in any features and details of construction hereafter more fully set forth in the specification and claims.

Referring to the drawings in which similar numerals indicate the same parts throughout the several views,

Figure 1 is a side elevation in section of a 50 sleeve valve engine equipped with a device of this invention. The engine mechanism itself is the subject matter of one or two

patents heretofore issued to me and a pending application Serial Number 317,701, filed August 15, 1919.

Fig. 2 is a detail view taken on the line 2-2 of Fig. 1 showing the preferred form of valve mechanism for controlling the admission of air to the atomizer or injector, and the governing mechanism (not appearing in Fig. 1) applied thereto.

Fig. 3 is a view corresponding to Fig. 2 of an alternative form of valve mechanism for the same purpose.

Fig. 4 shows the application of the valve 65 mechanism of Fig. 3 to the oil intake nozzle.

Fig. 5 is a vertical sectional view of the upper portion of a conventional form of puppet valve mechanism having the device of this invention applied thereto and showing an alternative construction of valve mechanism for controlling the supply of air 70 to the atomizer or injector.

Fig. 6 is a detail of a cam drive mechanism for actuating the valve shown in 75 Fig. 5.

Fig. 7 shows an alternative type of air nozzle.

The mechanism of this invention may be applied to engines of this type of any number of cycles and any number of cylinders 80 without departing from the invention. In the drawings only a single cylinder is shown. In the case of multiple cylinder engines the mechanism here shown or essential parts 85 thereof would be duplicated.

Referring to Fig. 1 the conventional form of engine shown comprises a main cylinder 10 in which travels the usual piston 12 driven by the crank mechanism 14, in crank case 16 90 the intaking and exhausting of air being controlled by the rotary sleeve valve 18 driven by the gear mechanism 20, air being supplied to the top of the cylinder above the piston through an intake pipe 22 controlled 95 by said valve, all as set forth in prior disclosures heretofore referred to.

In applying the mechanism of this invention to the engine just referred to the fuel intake nozzle 24 is introduced into pipe or 100 passage 22 at a point conveniently close to the engine cylinder. A constant supply of fuel oil is maintained in a float chamber 26 supplied by a pipe 28 conveniently placed

adjacent to nozzle 24. This float chamber mechanism which is a device well known in the art, and therefore not described in detail, is so adjusted and placed that fuel material is maintained on a level with or slightly below the upper or discharge end of nozzle 24.

Entering the pipe 22 at right angles to the top of nozzle 24 is an air pipe 30 having its discharge end or nozzle 32 immediately adjacent to and directed over the top of nozzle 24 so that when a stream of air is driven through nozzle 32 over nozzle 24 it, under the ordinary atomizer principle, sucks liquid from nozzle 24 and carries it through into the top of cylinder 10.

The air under pressure is supplied to pipe 30 through the valve case 34 of Fig. 1 which may be internally the valve mechanism of Figs. 2 or 3. The air is supplied to this valve case and its inclosed valve through a pipe 36 in turn supplied from an air chamber 38 filled by an air pump 39 driven by gear mechanism 42 from the gear mechanism 20 heretofore referred to.

The valve device of Fig. 2 consists of the exterior casing 34 which appears in end view Fig. 1 attached rigidly to the engine by any suitable means as, for instance, the screw 36; there being in this case an adjustable rotary valve 38 which controls the passage of air from pipe 36 to pipes 30 and 30^a. view Fig. 1 attached rigidly to the engine. The designation 30^a is used to indicate grammatically a pipe identical with 30 leading to another cylinder not shown. The valve 38 which thus controls the passage of air in the nozzle or nozzles 32 is, as shown, of cylindrical form and is provided adjacent to each pipe 30 or 30^a which it controls with a port 40 through which the air has to pass in order to go from pipe 36 to the nozzle. Each port 40 is made of triangular form as shown, longer than the width of the entrance to the adjacent pipe 30. The cylindrical valve 36 is made reciprocable by mechanisms to be described within the case 34 so that different portions of this port 40 may be made to register with the intake of the adjacent pipe 30. Obviously when the wide end of this port registers with the pipe entrance and the valve 36 is rotated at a given speed there will be opportunity for greater quantity of air to pass through the port than when the narrower portions of the port are passing over the entrance to pipe 30. In other words, the port in valve 38 is open for a longer period when the wide end of the port is passing pipe 30 than when the narrow end is passing.

It is to be noted that one side of triangular port 40, in the particular case here illustrated the upper side 41, runs parallel to the axis of the valve casing and the rotatable valve. In practice the valve is so connected

in relation to the engine crank shaft 60 that the valve always closes on this line 41, *i. e.*, when the line passes off from port 30 when the piston is in its full lowered position. As this line 41 is parallel to the axis of the valve 70 this takes place every time regardless of the longitudinal position of the valve port. The result of this is that by moving the valve longitudinally the point of valve opening may be varied without changing the point 75 of closing.

The valve 38 is open at its right hand as shown to pipe 36 in all positions of movement. The left hand end of the valve cylinder is closed by a head 42 to which a reciprocatable rod or shaft 44 is secured by any suitable means as, for instance, nut 46 in connection with the squared shoulder 48 through the cylinder head. This shaft carries a spline 50 with which it passes through the gear 52 journaled in a suitable support 54 carried by the engine. This gear 54 is rotated by suitable gearing which in the particular case here illustrated takes the form of the gear 56 driven by shaft 58 in turn 90 driven in any convenient manner without novelty and so not shown from the crank shaft 60 of the engine. In constructing the device the gearing or other mechanism which drives this valve from the crank shaft 95 is so arranged and proportioned that the valve 38 will rotate properly in relation to the movement of the piston to admit air through this valve mechanism to the nozzle 32 to propel air over and consequently draw oil from nozzle 24 into the upper end of the cylinder 10 at the proper time in relation to the stroke of the piston 12. For example, and preferably when the piston is on its down stroke or in its inhalation movement. 100

As heretofore noted the spline 50 on shaft 44 insures the gear 52 rotating the shaft and consequently the valve 38. This spline is of such a character that the shaft 44 is reciprocatable through gear 52, even when rotating, 110 to vary the lengthwise position of the valve 38 and consequently the ports 40 as heretofore described, to give a stronger or weaker charge to vary the power of the engine.

Shaft 44 is reciprocated by the governor 115 mechanism shown in the left hand upper corner of Fig. 2, the mechanism in the particular form illustrated, consisting of a conventional gear driven fly-ball governor mechanism 62 which is connected to the 120 shaft by the conventional bell crank mechanism 64 and intervening link 66. As the governor operates in the ordinary manner the bell crank 64 is rocked and reciprocates the shaft 40 through the pin and slot connection 68. The governor is driven by the engine by any suitable means without novelty, well known in the art and therefore not shown.

Obviously the bell crank 64 or other shift- 130

ing mechanism for the shaft 44 may be manually operated without the use of the governor mechanism if so desired.

The governor 62 is so adjusted that it 5 positions valve 38 with its wider end in register with pipe 30 under heavy load conditions and shifts to prevent acceleration of the engine to the narrower valve opening when the load is taken off the engine.

10 In the alternative valve construction of Fig. 3, a casing 70 corresponding to casing 34 is provided as before and in it is placed a rotary cylindrical valve 72 open at its right hand and closed at its left hand end so that 15 the left hand end can have the drive mechanism 74 corresponding to the drive mechanism in Fig. 2 applied thereto. The valve mechanism 72 differs however from that of Fig. 2 in that hot air or gas from the 20 exhaust of the engine is fed into cylinder 72 through a pipe 76 and passes out through the other end through ports 78 and 80 through an exhaust pipe 82, thus supplying heat to the interior of the valve mechanism, 25 while opposite sides of the cylinder 70 are perforated to make air intake ports 84 and 86, the latter leading to the nozzles 88 corresponding to nozzle 32, and the valve cylinder 72 has diametrically through it triangular pipes 90 of a cross section substantially like ports 40 in Fig. 2 so that as cylinder 72 is reciprocated different cross widths of these pipes are brought in register with the intake and exit ports 84-86 30 referred to, whereby air from nozzles 88 admitted by supply pipe 92 corresponding to pipe 36 is regulated in the same manner as in the preferred construction in Fig. 2.

The object of passing hot air through the 40 cylinder 72 around the pipes 90 is to heat the air delivered by pipe 92 as it passes to nozzles 88, thus to assist the air in readily volatilizing the heavier grades of oil or other fuel drawn out of nozzle 24.

45 In the construction shown in Fig. 5 a nozzle 100 is introduced into air intake passage 102 leading to puppet valve 104. Air is supplied to this nozzle 100 through pipe 36 or otherwise through a pipe 106; whose 50 communication with the nozzle is controlled by a reciprocatable valve 108 seatable at 110 in the obvious manner. Valve 108 is carried on a rigid arm 112 which in turn carries a roller 114 supported by a cam 116 55 driven by shaft 118. This shaft 118, shown in detail in Fig. 6, is rotatably and reciprocatably mounted in bearings 120. It is driven from its right hand end by spline gear mechanism identical with the mechanism 50-52-54-56-58 of Fig. 2 and not shown in Fig. 6. It is reciprocatably through a lever mechanism 124 pivoted at 126 which may be either governor or hand operated through the rod 128. Between the 60 bearings 120 shaft 118 carries the cam 116,

which has an inclined face 130 shown in Fig. 6, but not in Fig. 5, adapted to vary its effective diameter as regards wheel 114 when the shaft 118 and consequently the cam is shifted lengthwise of the shaft and to thereby vary the stroke and consequently the opening created by valve 108 and thereby vary the quantity and the period during which air is delivered by nozzle 100 into the cylinder.

75 The foregoing is the subject matter of a divisional application, Serial Number 382,874, filed May 20, 1920.

In order not to limit this application to the particular form of air nozzle driving 80 over an upright fuel nozzle hertofore described an alternative nozzle construction is shown in Fig. 7 in which the air is supplied to pipe 130 and the fuel is supplied to pipe 132, the discharge nozzle 134 for 85 the oil being properly adjusted or focused within the air nozzle 136.

The special advantages of applying this invention to combustion engine cylinders are that large ports and passageways may 90 be used for delivering air to the engine so that there is no question whatever about the engine having a maximum volume of air in it when the piston has completed its down stroke, and that higher velocity air is 95 separately provided for atomizing heavy fuels which are not adequately handled by the normal suction of the piston hertofore referred to.

It is to be noted that the independent air 100 nozzles are located in immediate proximity to the engine cylinder so that the atomized fuel is delivered through the usual valve controlled cylinder port directly into the combustion space of the cylinder instead of 105 into the manifold as in prior constructions. This direct delivery has the advantage that the fuel oils do not have a chance to condense in the manifold and does away with all frosting of the intake pipe. It permits 110 the use of heavy, cheap oils.

Having thus described my invention what I claim as new and desire to secure by Letters Patent is:—

1. In mechanism of the class described, 115 in combination with the combustion space of an internal combustion engine provided with an air intake passage, a fuel nozzle adapted to deliver oil, an independent air nozzle adapted to take oil from the fuel 120 nozzle to the combustion space, means independent of the engine intake for supplying air under pressure to said air nozzle, and means positively driven by the engine crank shaft for regulating the period of time during 125 which air is delivered by said air nozzle in proportion to the angular rotation of the crank shaft.

2. In mechanism of the class described, 130 in combination with the combustion space

of an internal combustion engine provided with an air intake passage, a fuel nozzle adapted to deliver oil, an independent air nozzle adapted to take oil from the fuel nozzle to the combustion space, means independent of the engine intake for supplying air under pressure to said air nozzle, and means positively driven by the engine crank shaft for varying the volume and duration 10 of air delivery by said nozzle in proportion to the angular rotation of the crank shaft.

3. In mechanism of the class described, a cylindrical valve casing provided with intake and exhaust air ports, one of which is 15 in the cylindrical wall of the casing, a valve member rotatable and reciprocatable within said casing over said last mentioned port there being a port in the valve member adapted to intermittently register with the 20 air port in the cylindrical wall of the casing, one of said registering ports being of irregular shape and larger than the other whereby varying the position of the valve member changes the delivery of material passed by 25 the device.

4. In mechanism of the class described, a cylindrical valve casing provided with intake and exhaust air ports, one of which is in the cylindrical wall of the casing, a valve 30 member rotatable and reciprocatable within said casing over said last mentioned port there being a port in the valve member adapted to intermittently register with the air port in the cylindrical wall of the casing, 35 one of said registering ports being of triangular form extended along the axis of the cylinder and larger than the other whereby varying the position of the valve member changes the delivery of material passed by 40 the device.

5. In mechanism of the class described, a cylindrical valve casing provided with intake and exhaust air ports, one of which is in the cylindrical wall of the casing, a valve 45 member rotatable and reciprocatable within said casing over said last mentioned port there being a port in the valve member adapted to intermittently register with the air port in the cylindrical wall of the casing, 50 the port in the valve member being larger than the other whereby varying the position of the valve member changes the delivery of material passed by the device.

6. In mechanism of the class described, a 55 cylindrical valve casing provided with intake and exhaust air ports, one of which is in the cylindrical wall of the casing, a valve

member rotatable and reciprocatable within said casing over said last mentioned port there being a port in the valve member 60 adapted to intermittently register with the air port in the cylindrical wall of the casing, one of said registering ports being of triangular form extended along the axis of the cylinder and larger than the other and located in the valve member whereby varying the position of the valve member changes the delivery of material passed by the device. 65

7. In mechanism of the class described, in combination with an engine, a cylindrical valve casing having an intake port in one end and a discharge port in the cylindrical side thereof leading to the engine, a cylindrical valve member inside the casing open at all times to the intake port and provided 70 in its cylindrical wall with a port of irregular shape and of greater area than the discharge port adapted to intermittently register with it as the valve rotates, means for rotating the cylindrical valve within the 75 casing and means for reciprocating the valve within the casing whereby the effective area of the opening through the cylindrical valve to the discharge port of the casing is varied for the purposes set forth. 80

8. In mechanism of the class described, in combination with an engine, a cylindrical valve casing having an intake port in one end and a discharge port in the cylindrical side thereof leading to the engine, a cylindrical 90 valve member inside the casing open at all times to the intake port and provided in its cylindrical wall with a port of irregular shape and of greater area than the discharge port adapted to intermittently register with it 95 as the valve rotates, means for rotating the cylindrical valve within the casing, means for reciprocating the valve within the casing whereby the effective area of the opening through the cylindrical valve to the discharge port of the casing is varied, and governor mechanism adapted to be driven by the engine to which the valve mechanism is applied, arranged to reciprocate said valve within the cylindrical case, for the purposes 100 set forth. 105

In witness whereof, I have hereunto subscribed my name in the presence of two witnesses.

JAMES A. CHARTER.
